PERCY WALTER DRUITT, OF SURREY, ENGLAND, ASSIGNOR TO EDWARD HERON ALLEN
AND ARTHUR FRANK DE FONBLANQUE, BOTH OF LONDON, ENGLAND.

MOLD FOR TYPOGRAPHIC OR TYPE-FOUNDRY APPARATUS.

1,149,119.

Specification of Letters Patent.

Patented Aug. 3, 1915.

Application filed January 12, 1912. Serial No. 670,905.

To all whom it may concern:

Be it known that I, PERCY WALTER DRUITT, a subject of the King of Great Britain, residing in Surrey, England, and whose post-office address is Baron Cottage, London Road, Mitcham, in the county of Surrey, England, have invented certain new and useful Improvements in Molds for Typographic or Type-Foundry Apparatus, of 10 which the following is a specification.

This invention relates to type molds of casting machines for single foundry type or of type setting and casting machines such as described in United States patent specifications Nos. 675827, 675829 and 690720, wherein a line of matrices is composed and justified and individual character types and spaces are cast therefrom and then assembled in a galley.

20 The objects of this invention are to insure uniformity of set thickness in the cast type, and to insure metal tight abutment of the mold surfaces which form the foot and tang of the type and to permit withdrawal 25 of the body blade and tang blade without disturbing the relation of this side blocks with the remainder of the mold.

With these objects the body blade and the tang blade, which are constructed in separate pieces, are, according to the present invention, so correlated that the movement of the tang blade on the forward stroke, which determines the set thickness of the type permits the body blade to be driven forward 35 by a spring-urged set wedge against the matrix, independently of any further forward movement of the tang blade. Further, in order to obviate displacement of the alining piece (which coöperates with the body 40 blade to hold the matrix in casting) relatively to the end surfaces of the side blocks of the mold by reason of unequal expansion of the parts of the mold, the alining piece is, according to the present invention, secured upon the front plate of the mold, which being in intimate contact with the water cooled side blocks and nowhere touching the angle plate of the mold, insures an invariable distance between the face of the 45 alining piece and the end surfaces of the side blocks.

These and other features of the present invention are illustrated in the accompanying drawings in which—

55 Figure 1 is a front elevation of the mold

with the front plate removed; Fig. 2 a plan view of the same with the top side block removed; Fig. 3 a front elevation showing the front plate of the mold and adjustable alining piece but no matrix is depicted; Fig. 60 4 a plan of the same; Fig. 5 a plan of the mold with front plate removed and showing the nick pin; Fig. 6 a section on line 6—6 of Fig. 5; Fig. 7 an end elevation of the side blocks and nick pin; Fig. 8 a section on line 8—8 of Fig. 6; and Fig. 9 a perspective view of the forward part of the nick pin. Figs. 10 and 11 are horizontal sections through the mold cavity of the apparatus shown in Figs. 1 and 3, respectively; 70 and Figs. 12 and 13 are vertical sections of the same, also through the mold cavity.

Referring first to Figs. 1 and 2, it will be seen that the mold is constructed with the body blade *a*, and the tang blade *b* in separate pieces, which are so correlated that when the tang blade is driven forward on the stroke which determines the set thickness of the type, by contact of the set piece *a'* of the body blade with the set notch of 80 the matrix, *n* (Figs. 11, 13) the forward movement of the tang blade *b* under the action of its spring *b'*, releases the body blade *a* so that it can be driven forward independently against the matrix, this being 85 effected in the case of machines such as described in the before mentioned specifications by a set wedge *c* operated by a cam on the mold shaft, the tang blade following under the action of its spring. 90

Normally the tang blade is arrested in the appropriate position for casting, that is with its front face flush with that of the body blade, by reengagement with the body blade, a projecting lug *b*² on the tang blade 95 having movement in a slot *a*² of the body blade for this purpose, but even if the tang blade is arrested before these surfaces are flush, as for example by reason of the tang blade becoming slightly distorted and defective, the independent setting of the body blade by the set wedge *c*, previously referred to but which in this case is urged forward by the spring *c'*, insures the constancy of 100 the set thickness of the type which is being cast, there being sufficient relative movement possible between the lug *b*² and the shoulders at the end of slot *a*² to insure this.

After the type is cast, the set wedge *c* is withdrawn and the tang blade is retracted 110

positively by means of the cam driven lever d , pin e' on sleeve e , and adjusting nuts f on the link b^3 operating the tang blade, and brings the lug b^2 into engagement with the rear shoulder of the slot a^2 , thereby releasing the body blade, so as to enable the matrix to be withdrawn.

It is to be understood that the set wedge c and lever d are actuated by cams upon the 10 driving shaft of the casting machine, (e. g., the shaft known as the mold shaft in the type setting and casting machine in connection with which this invention is more particularly described), and that the cam which 15 actuates lever d is of such a character as to become inoperative during part of the revolution of the driving shaft so as to allow the tang blade b to be moved by the spring b' for setting the body blade a against the 20 matrix.

The type is extruded from the mold for delivery therefrom by the cross slide m , by again advancing the tang blade so as to complete the forward stroke of the body blade 25 and tang blade, which, for this purpose are positively driven forward the required distance by lever d , the tang blade reengaging the body blade so that the two move forward together with their front faces flush, 30 thereby ejecting the type from the mold cavity o into the path of the cross slide m by which it is delivered from the mold under the action of appropriate reciprocating mechanism which forms no part of the present invention and consequently is not illustrated.

Another cause of variation of set thickness resides in the liability of the alining piece g , (Figs. 3 and 4), between which and 40 the set piece a' of the body blade a the matrix is held in casting, being displaced relatively to the end surfaces of the side blocks h , h' of the mold by reason of unequal expansion in the parts of the mold and in particular by reason of the expansion of the angle plate i upon which the alining piece has hitherto been carried. According to the present invention, the alining piece is secured upon the front plate j of the mold 45 which is preferably formed with a transverse groove j' to accommodate the alining piece g . As the front plate j is in intimate contact with the side blocks h , h' and nowhere touches the angle plate, the temperature of the side blocks and of the front plate 50 does not vary materially and thus there is no unequal expansion and no consequent variation in the distance between the face of the alining piece g and the end surfaces 55 of the side blocks h , h' and therefore no variation on this account in the set thickness of the type. The position of the alining piece both transversely and longitudinally with respect to the front plate is preferably 60 capable of adjustment so that the distance 65

of the bottom edge of the alining piece relative to the type aperture and the distance of its front edge from the end surfaces of the side blocks, can be accurately set.

The former adjustment may be effected 70 by means of cone headed set screws g' and clamping screws g^2 . The bodies of the screws g^2 pass through enlarged holes in the alining piece g and screw into the front plate j . By turning screws g' in opposite directions, 75 while the clamping screws g^2 are set so that the piece j is not clamped by these heads, the transverse position of the alining piece can be adjusted and the piece then fixed in position by operating screws g^2 . The adjustment 80 of the piece g longitudinally with respect to the front plate may be effected by means of set screws g^3 which abut against the rear surface of the adjusting piece and work partly in screw threaded grooves in 85 the front plate j and partly in corresponding grooves in a loose clamping plate j^2 which is secured by screws j^3 to lock the set screws g^3 after the adjustment has been effected.

In order that the body blade a and tang 90 blade b of the mold may be withdrawn without disturbing the relation of the side blocks h , h' with the remainder of the mold, the groove h^2 in the top side block h' in which the nick pin k (Figs. 5 to 9) is fitted is, according to the present invention, carried 95 right through the block and the rear end of the nick pin is extended to be flush with the rear face of the side block, a keep plate h^3 being provided for this end of the nick pin 100 to abut against. The plate h^3 is detachably mounted by means of one or more screws or studs h^4 on the rear face of the side block h (Fig. 5), the loosening or withdrawal of the screw or screws h^4 enables the keep plate 105 to be swung aside or removed altogether. The nick pin is formed with a shoulder k' near its forward end by cutting away part thereof, and the groove h^2 in the side block terminates at its forward end in a recess l 110 having a shoulder l' at its forward end for the shoulder k' to abut against.

The groove h^2 for the nick pin in the upper side block, instead of being of the same transverse section as the nick pin, is 115 preferably formed so as to provide a certain amount of lateral clearance for the nick pin in the groove, in order that the body blade a , one side of which is grooved to embrace the nick pin, may be enabled to fit 120 snugly in the casting position against the co-operating surfaces of those parts of the mold which form the foot of the type.

It will be understood that in the mold herein described and illustrated the mold 125 cavity is formed by members which do not differ essentially from the corresponding members of the mold described in the co-pending application Serial No. 625450, the two side blocks h , h' forming two walls of 130

the mold cavity and also serving to guide the body blade and the tang blade which together form a third wall, while the cross slide *m* forms the fourth wall of the mold cavity and the matrix itself the fifth wall.

Having thus described the nature of the said invention and the best means I know of carrying the same into practical effect, I claim:—

10 1. A type mold for type casting machines such as herein referred to, comprising a tang blade and a body blade capable of relative movement, means operating to move the tang blade and body blade simultaneously, 15 and a spring-urged set wedge adapted to drive the body blade forward against the matrix independently of any movement of the tang blade, substantially as described.

20 2. A type mold for type casting machines such as herein referred to, comprising a front plate, two side blocks, a body blade and an alining piece coöperating with the body blade to hold the matrix in casting, said alining piece being secured upon the 25 front plate of the mold, substantially as described.

3. A type mold for type casting machines such as herein referred to, comprising a

front plate, two side blocks, a body blade and an alining piece coöperating with the 30 body blade to hold the matrix in casting, said alining piece being adjustably secured upon the front plate of the mold, and means for shifting the alining piece both transversely and longitudinally with respect to 35 the plate and for clamping the alining piece upon the plate, substantially as described.

4. A type mold for type casting machines such as herein referred to, comprising a pair of side blocks, one of said side blocks having 40 a groove formed therein, said groove being carried through the block to the rear face thereof, a nick pin accommodated in said groove and extending rearwardly so as to be flush with the rear face of the side block, and 45 a detachable keep plate secured to the rear face of the side block in abutment with the rear end of the nick pin, substantially as described.

In testimony whereof I have signed my 50 name to this specification in the presence of two subscribing witnesses.

PERCY WALTER DRUITT.
